UNITED STATES PATENT OFFICE.

ARTHUR H. BURNS, OF PENN YAN, NEW YORK.

OAR.

Application filed November 29, 1926. Serial No. 151,490.

This invention relates to oars and more particularly to an oar employed for propelling row-boats and other small boats. At the present time row-boats are usually propelled by oars fitted into oar locks at the sides of a row-boat and the operator occupies a seat in the boat forwardly of the oar locks and faces the stern or rear end of the boat. This has been found objectionable as the person rowing the boat is facing rearwardly and, therefore, finds it difficult to maintain a straight course and also is liable to accidentally collide with other boats or obstructions in a body of water.

Therefore, one object of the invention is to provide an oar which may be operated in the usual manner but with the operator facing the bow of the boat instead of the stern.

It has also been found that when an oar of a conventional construction is in use it is liable to slip out of an oar lock thereby preventing proper rowing of the boat and also is liable to slip through the oar lock and float away from the boat if released without being lifted from the lock or drawn inwardly. Therefore, another object of the invention is to provide the oar with an improved mounting by means of which it may be securely attached to a boat but permitted to have proper movement imparted to it while rowing.

Another object of the invention is to allow a relatively long swing or working movement to be imparted to the blade portion of an oar when a short movement is imparted to the handle end of the oar.

Another object of the invention is to permit the blade portion of the oar to be removed from its mounting and employed as a paddle if so desired and to also allow the blade and handle portions of the oar to be securely locked in the mounting against swinging movement relative to each other if it is necessary to use the oars in a boat having ordinary oar locks.

The invention is illustrated in the accompanying drawing, wherein—

Figure 1 is a view showing the mounting for the blade and handle portions of an oar partially in top plan and partially in longitudinal section, fragments of the blade and handle of the oar being shown in top plan;

Fig. 2 is a longitudinal sectional view taken on the line 2—2 of Fig. 1, and

Fig. 3 is a transverse sectional view taken on the line 3—3 of Fig. 1.

The oar constituting the subject-matter of this invention includes a handle portion, indi-

cated by the numeral 1, and a blade portion, indicated by the numeral 2. The blade and handle portions of the oar are of a conventional construction and only fragments thereof have been shown in the drawing. The mounting for the blade and handle includes a frame having upper and lower plates 3 and 4 which may be formed of any metal desired having sufficient strength. These plates 3 and 4 are disposed one above the other and connected by bolts 5 and 6 which pass through openings formed in the upper plate 3 and are screwed into threaded openings formed in the lower plate 4. Sleeves 7 and 8 are fitted upon the bolts 5 and 6 and constitute spacers to retain the plates in proper spaced relation to each other and prevent them from being moved too close together when the bolts are tightened.

Handle and blade carriers 9 and 10 which, if desired, may be referred to as heads for the handle and blade are disposed between the plates of the frame. The blade and handle carriers are formed of metal and are provided with openings 11 and 12 through which the sleeves 8 pass. It will thus be seen that the bolts 6 will constitute axles for the carriers and the sleeves 8 may constitute bushings for them. The inwardly facing end portions of the carriers are formed with arcuate edges cut to provide gear teeth 13 and 14 which intermesh so that, when the handle carrier is rotated, rotary motion will be transmitted to the blade carrier and a swinging movement imparted to the oar blade. By an inspection of Fig. 1, it will be seen that the circle of which the arcuate edge of the handle carrier forms a portion is of greater diameter than the circle of which the arcuate edge of the blade carrier forms a portion. Therefore, when the handle of the oar is swung a short distance a long swing will be imparted to the blade of the oar and a boat may be rapidly propelled through the water with a minimum exertion on the part of the operator.

In order to connect the mounting with the side of a boat, there has been provided a hinge leaf 15 having the usual openings therein to receive fastener screws 16 and also preferably provided with openings to receive bolts 17 of sufficient length to pass entirely through the gunnel 18 of a row-boat. The hinge leaf is provided with the usual hinge sleeves 19 through which are passed a hinge pin or axle 20. Openings are drilled in the

end portion of the hinge pin to receive securing keys 21, one of which is carried by a chain 22. The chain 22 is engaged with a ring 23 carried by the plate 3 so that, when 5 the other cotter key is removed and the hinge pin withdrawn, it may be suspended by the chain and not be liable to drop into the water and become lost. Bearings 24 are riveted or otherwise rigidly secured against 10 the under face of the lower plate 4 of the frame in proper spaced relation to each other to be received between the hinge sleeves 19 and are formed with alined openings through which the hinge pin passes, as 15 shown in Fig. 3. It will thus be seen that when the hinge pin is in place the frame may be tilted transversely of the gunnel in order to move the blade of an oar into and out of the water while rowing the boat.

20 If it is desired to employ the oar in connection with an oar lock of a conventional construction, the blade and handle portions of the oar must be prevented from having swinging movement relative to each other.

25 Therefore, I have provided pins 25 which are carried by chains 26 engaged with rings 27 carried by the upper plate 3 of the frame, and these pins 25 are adapted to be passed through openings 28, 29 and 30 formed in 30 the frame and blade and handle carriers when the blade and handle are disposed in alinement and the openings 29 in registry with the openings 28 and 30. By this arrangement the blade and handle portion of 35 the oar may be held stationary and the oar fitted into an oar lock of a conventional construction and operated in the usual manner. It should also be noted that, if desired, the 40 bolt 6 which pivotally mounts the blade carrier may be removed and thereby release the

blade and its carrier so that they may be withdrawn from the frame or housing and the blade portion of the oar employed as a paddle. I have thus provided an oar which may be operated in connection with oar locks 45 of a conventional construction, as a bow facing oar, or as a paddle.

If desired, the gear forming portions of the carriers may be of the same size so that swinging movement of the blade and handle 50 will be the same.

Having thus described the invention, I claim:

In an oar, a frame comprising upper and lower plates, fasteners extending through the side edge portions of said plates, other fastenings extending through the plates on the medial longitudinal line thereof, sleeves upon said fasteners between the plates to retain the plates in spaced relation to each other, a blade carrier and a handle carrier between said plates, said carriers having semi-circular heads rotatably received about the sleeves on the last-mentioned fasteners and having arcuate inner edges formed with intermeshing gear teeth, bearing brackets secured against the under face of the lower plate adjacent opposite said edges thereof, a hinge leaf having sleeves spaced from each other along its upper edge to be disposed at the outer sides of said brackets, means for securing said leaf rigidly to the gunnel of a boat, a pin passed through the sleeves and bearing brackets to pivotally connect the frame and hinge leaf, and means engaged with the ends of said pin and the upper frame plate to prevent loss of the pin.

In testimony whereof I affix my signature.

ARTHUR H. BURNS. [L.S.]
